UNITED STATES PATENT OFFICE.

MYRON J. WHIPPLE, OF MONROE, MICHIGAN, ASSIGNOR TO THE WESTERN PAPER BOX COMPANY, OF DETROIT, MICHIGAN, A CORPORATION OF MICHIGAN.

ADJUSTABLE CARDBOARD EASEL.

Application filed December 22, 1921. Serial No. 524,063.

To all whom it may concern:

Be it known that I, MYRON J. WHIPPLE, a citizen of the United States, and a resident of Monroe, in the county of Monroe and 5 State of Michigan, have made an invention appertaining to Adjustable Cardboard Easels; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention has for its object to provide an easel for the support of articles such as advertising cards or figures made from cardboard, and wherein means is provided for readily adjusting the easel as to the angular 20 position in which it holds the object. It also has for its object to provide a means for locking the parts of the easel in its adjusted position.

The invention may be contained in easels 25 which in their details may vary. To illustrate a practical application of the invention I have selected a cardboard easel containing the invention and shall describe it hereinafter. The easel selected is illustrated in 30 the accompanying drawings.

Figure 1 of the drawings is a front view of the easel when it has been opened. Fig. 2 illustrates the blank from which the easel may be formed. Fig. 3 illustrates the means 35 whereby the easel may be locked in its adjusted position.

1 in the figures is a blank having a central portion 2 that is divided from the winged portions 3 by scored lines 4, whereby 40 the wings 3 may be readily bent along the scored lines 4. The lower ends of the wings 3 are preferably inclined with respect to the lower end of the central portion 2, and the upper corners of the wings 3 and the central portion 2 adjoin. Moreover, the central portion 45 is preferably rectangular in form and the wings are triangular. When, therefore, the wings are bent at a slight angle to the central portion they form with the central 50 portion a base that is defined by the lower edges of the wings and of the central portion and a line joining the outer lower corners of the wings. Thus to increase the base area or to increase the depth of the base as measured 55 from the central portion, the wings

may be bent with respect to the central portion so as to form smaller angles with the central portion. Also if desired to vary the angle position of the central portion as measured in the plane of the central portion it 60 may be done by moving one of the wings farther back to form a lesser angle with the central portion than the other of the wings is placed. This is of advantage when a picture or figure is secured to the central 65 portion at a slight angle, which often occurs when figures or cards are secured to the easels by unskilled or careless individuals, and it is desired to correct the position of the card or figure when the easel is set up. If 70 the figure tilts to the right or to the left to an undesired degree the easel may thus be adjusted to bring the figure upright with reference to a transverse plane. The invention thus provides a means for adjusting 75 the easel both as to angles extending forward or back or as to angles extending right or left.

I have also provided a means for locking the easel in its adjusted positions. A 80 substantially arcuate cut is made in the central part of the blank and across the central portion 2 and also parts of the wings. The lower edge of the sector 5 is defined by a scored line 6 that extends across the central portion 2 of the blank and the cuts 7 that extend into the wings 3, so that when the wings are bent back the lower edge of the sector will remain in the plane of 85 the central portion 2. In order to yieldingly hold the wings in their adjusted position a portion of the edge may be provided with a plurality of scallops. Preferably the portions that are cut from the wings 90 are provided with the scallops. The sides 95 of the sector are cut so that the scallops will frictionally engage the edges of the wings produced in the formation of the sector, that is, the scallops are substantially in the line or arc described by the 100 corners 8 of the sector when the wings are moved angularly relative to the central portion 2 of the easel. The edges of the wings formed by cutting the sector will frictionally engage the scalloped portions of 105 the sector, but the wings may be forced along the scalloped edges when some pressure is applied. One wing may be pushed farther along than the other wing in order to adjust the angular position of the oblong cen- 110

tral portion 2 with reference to a transverse plane and both wings may be adjusted to any desired position to adjust the oblong central portion of the easel to any position with reference to any vertical plane extending at right angles to the central portion.

If desired, means may be provided for locking the planes to the sector in their adjusted positions. This may be done by the locking lips 9 that are formed from the wings by cuts and a scored line extending around the lips. The scored lines 10 may extend substantially in line with the scored line 6 and cuts 7. Preferably one of the cuts that surround the locking lips 9, such as the cuts 11, extend into the wings so as to leave projecting portions 12. When, therefore, the wings are to be adjusted, the sector 5 is bent rearwards on the scored line 6 and the wings 3 are bent angularly relative to the central portion 2, while the sector 5 is held so that its edges will pass between the projections 12 and the edges of the locking lips 9 formed by the cuts 11. The elasticity of the sheet material will cause the locking lips 9 to frictionally engage the sector 5 and the lips and the projections will hold the wing in any position that they may be placed with reference to the sector, although it will not hold it with the same rigidity that the scalloped edges will hold it. If, however, it is desired to lock the wings in their adjusted positions along the edge of the sector it may be done by forcing the lips 9 so that their surfaces will be located in the planes of the surfaces of the wings. To lock the wings in adjusted positions so that they cannot be moved therefrom without destroying at least the edges of the sector or of the wings in the vicinity of the sector the wings may be placed between scallops of the scalloped portion along the edge of the sector and the lips turned to locking positions, which will tightly engage the edge of the sector.

I claim:

1. In a sheet material easel having supporting portions hingedly movable relative to each other, a portion located in a transverse relation to the supporting portions and having an arcuate edge, one of the first named portions having a point in one of its edges that describes a path substantially coincident with the said arcuate edge portion when moved relative to the other of the first named portions, and a locking means for locking one of the first named portions to the transversely located portion at any point along the arcuate edge portion.

2. In a sheet material easel having three supporting portions, two of the said portions being hingedly connected to the remaining portion, a fourth portion of the sheet material also hingedly connected to

the said remaining portion and located in transverse relation to the first named portions and having substantially arcuate edge portions, each of the said two portions having a point movable in paths substantially coincident with the said arcuate edge portions, and means for locking each of the said two portions at any point along one of the said arcuate edges.

3. In a sheet material easel having three supporting portions, two of the said portions being hingedly connected to the remaining portion and having bottom edges extending at angles to the bottom edge of the said remaining portion when the said two portions are located in the same plane with the said remaining portion, a fourth portion of the sheet material also hingedly connected to the said remaining portion and located in transverse relation to the first named portions, and having substantially arcuate edge portions, each of the said two portions having a point movable in the paths substantially coincident with the said arcuate edge portions, and means for locking each of the said two portions at any point along one of the said arcuate edges.

4. In a sheet material easel having three supporting portions, two of the said portions being hingedly connected to the remaining portion, a fourth portion of the sheet material also hingedly connected to the said remaining portion and located in transverse relation to the first named portions and having substantially arcuate edge portions, each of the said two portions having a point movable in paths substantially coincident with the said arcuate edge portions, a clamp located on each of the said two portions for clamping the said transversely located portion at any point along one of the said arcuate edges.

5. In a sheet material easel having supporting portions hingedly movable relative to each other, a portion located in a transverse relation to the supporting portions and having an arcuate edge, one of the first named portions having a point in one of its edges that describes a path substantially coincident with the said arcuate edge portion when moved relative to the other of the first named portions, and a clamp located on one of the first named portions for clamping the transversely located portion at any point along the arcuate edge.

6. In a sheet material easel having a supporting portion, a wing hingedly connected thereto, a part located in transverse relation to the supporting part and the wing and having an arcuate edge, the wing having a point in one of its edges that describes a path substantially coincident with the said arcuate edge when moved relative to the supporting portion, the wing having a portion hingedly connected thereto and lo-

cated at one side of the arcuate edge portion for clamping the arcuate edge portion between the hingedly connected portion and the edge of the wing at any point along the 5 arcuate edge portion.

7. In a sheet material easel having a supporting portion, a wing hingedly connected thereto, a part located in transverse relation to the supporting part and the wing 10 and having an arcuate edge, the wing having a point in one of its edges that describes a path substantially coincident with the said arcuate edge when moved relative to the supporting portion, the wing having 15 a portion hingedly connected thereto and located at one side of the arcuate edge portion for clamping the arcuate edge portion between the hingedly connected portion and the edge of the wing at any point along 20 the arcuate edge portion when the hingedly connected portion is forced in position substantially in plane with the wing.

8. In a sheet material easel comprising three portions, one forming a supporting

panel, a second forming a wing, a third 25 forming an engaging member, the said portions hingedly connected to the first named portion along edges of the first named portion located substantially at right angles to each other, the third named portion having 30 an arcuate serrated edge portion located substantially in the path of one of the points of one of the edges of the second named portion when the second named portion is moved relative to the first named 35 portion and when the third named portion is in engaging position, the second named portion having a part movable relative to the second named portion for clamping the serrated arcuate edge portion of the third 40 named portion at any point along the arcuate edge portion and between the edge of the movable part and the edge of the second named portion.

In testimony whereof, I have hereunto 45 signed my name to this specification.

MYRON J. WHIPPLE.
